UNITED STATES PATENT OFFICE

CHARLES W. THOMPSON, OF WOLLASTON, MASSACHUSETTS, ASSIGNOR, BY MESNE ASSIGNMENTS, TO STEINER SALES COMPANY, OF SALT LAKE CITY, UTAH, A CORPORATION OF UTAH

ROLL TOWEL CABINET

Application filed January 31, 1929. Serial No. 336,518.

This invention relates to a towel cabinet, particularly the kind for attachment to a wall or door.

One of the objects of this invention is to provide a cabinet having a simple, reliable and inexpensive mechanism to permit withdrawal outside the cabinet of a limited length of toweling and to automatically draw the same toweling within the cabinet upon its release.

It is the constant endeavor of towel supply firms to reduce the cost of production of towel cabinets and to simplify the mechanism to which the toweling is attached so that it will rarely require adjustment or repairing and so that the toweling may be readily connected to it by a layman. The improvements illustrated and described herewith are the results of such endeavors.

Heretofore in wall cabinets provided with the automatic take-up mechanism, the toweling is left exposed near the front of the cabinet just below the bottom and it has been necessary to fasten an extra piece, such as a cleat, on the bottom, over which the toweling runs, in order to expose sufficient toweling so that the user may see where to grasp it. This cleat is unsightly in appearance, the toweling running over it and under the cabinet is wholly exposed, and a cabinet so constructed takes up more room. In my present invention, I have dispensed with the cleat and by using a sliding guard or curtain and providing an opening in the door, a larger portion of the toweling is visible to the user, it is easier for him to see and grasp it, the visible toweling is not wholly exposed, the cabinet occupies less space, it is more sightly in appearance and the lower ends of the sides of the cabinet serve as guides for the toweling which runs under the bottom.

With the above and other objects in view which will more readily appear as the nature of the invention is better understood, the same consists in the novel construction, combination, and arrangement of parts herein-after more fully described, claimed, and illustrated in the accompanying drawings.

In accordance with the rules of practice, reference is made to my co-pending appli-

cation, Serial No. 319,532, filing date—November 15th, 1928 and Serial No. 334,709, filing date—January 24th, 1929.

In the drawings:

Figure 1 is a perspective of the wall cabinet. 55

Figure 2 is a front elevation with the door open and parts broken away.

Figure 3 is a longitudinal cross-section on the line 3—3 of Figure 2. 60

Figure 4 is a plan cross-section on the line 4—4 of Figure 3.

Figure 5 is a partial left side elevation of the inner case.

Figure 6 is a perspective of the pawl. 65

Figure 7 is a perspective of the elevator.

Figure 8 is a plan view showing two lengths of toweling connected by a clasp.

Like numerals and letters of reference indicate corresponding parts in each figure. 70

As illustrated, the towel cabinet preferably consists of an outer frame or section 15 having a top 16, a bottom 17, a back 18, two sides 19 and a hinged door 20. The top 16 has holes 16a cut therein for ventilating purposes. The bottom 17 extends from just inside the door 20 to within a few inches of the back 18. This space 17a left between the bottom 17 and back 18 is for the purpose of inserting the hand to push the towel up the back as later explained. The front portion 17b of said bottom 17 is rounded so that the toweling may slide over it easily. A groove 17c, extending sidewise across the bottom between the two sides 19, is made in said bottom just back of the front portion 17b. A curtain or guard 30, later explained, normally rests in said groove 17c, and thereby holds the inner case 22 inside the outer frame 15 when the cabinet is in use. This bottom 17 is mounted in the sides 19 and is inset up from the bottom of said sides an inch or more, so that said sides serve as guides for the toweling which runs over the front edges of said bottom 17 and directly under it. A hole 19a is made in each side 19 so the holes are located opposite each other, in one of which holes a spring 19b is mounted, which spring makes it possible to insert and remove a locking bar later described. The door 20 is mounted on the sides 80

85

90

95

100

19 by means of hinges 20a and the lower part of the door has a large center opening 20b cut therein which serves to make part of the toweling visible. The upper part of the 5 door 20 has a mirror 20c set therein and at one side is a locking device 20d, so that persons may be kept from tampering with the inner mechanism or toweling.

Slidably mounted within the outer frame 10 15 is an inner case or section 22 having a top 23, a bottom 24, a partial back 25 and sides 26. The top 23 has holes 23a cut therein corresponding with the holes 16a for ventilation of the soiled towel compartment. Narrow 15 slots 23b are cut in the under side of the top at each end into which the sides 26 fit. Attached to the under side of the top 23 at each end are top joining pieces or cleats 23c, and a screw 23d is screwed into each piece 23c and 20 the side 26 to hold the top and sides together. Two small holes 23e are cut in the top 23 through both of which a chain, later described, passes. The bottom 24 has slots 24b cut in the upper side at each end into which 25 the sides 26 fit. Attached to the upper side of the bottom 24 at each end are bottom joining pieces or cleats 24c, and a screw 24d is screwed into each piece 24c and the side 26 to hold the top and sides together. Rubber 30 bumpers 24e are attached to said bottom near the back end on which an elevator E, later described, normally rests. The back 25 extends from the under side of the top 23 less than half way down and is fitted into slots cut 35 in the sides 26, being inset from the rear edges of the sides 26.

The sides 26 of the inner case 22 have a cleat 26a fastened to the front portion of said sides which makes the sides of this point considerably thicker, thereby providing a space 40 between the side 26 and the outer frame side 19 in which space a sprocket and chain mechanism operates, later referred to. A notch 26b is cut in the front edge of one of the 45 sides 26 to hold the elevator chain as later explained. Near the front edge of each side 26 a vertical slot 26c is cut extending from top to bottom in which slots 26c a towel guard or curtain 30 slides. The top edge of 50 this curtain 30 is rounded and it has a front projection 30a near the top, over which clean toweling passes. This projection holds the toweling away from the body of the curtain so the fingers may readily grasp the toweling. 55 A horizontal slot 26d is cut in each side 26 through which slots a locking bar 31 extends, which bar is mounted in the holes 19a. This bar 31 prevents the inner case 22 from being pulled out of the outer frame 15, although it may be partially pulled out, being stopped when the bar 31 contacts with the back end of the slots 26d. It also serves as a towel rod. In the rear portion of said sides 26 about one-half way up a towel rod 32 is 60 rotatably mounted in holes 26e cut into said

sides. In the back portion of said sides 26 a vertical slot 26f is made which extends from top to bottom, in which slots an elevator E runs. The rubber bumpers 24e are located adjacent the bottom of said slots 26f 70 and extend part way into them. Slots 26g are cut in the upper portion of said sides 26 part way through which extend from the vertical slots 26c horizontally towards the back and then diagonally downward. 75

This inner case 22 is divided into an upper chamber 34 and a lower chamber 33 by means of a curved division plate 35. This division plate 35 is mounted in the sides 26 and extends from a point more than half-way up the inner case 22 to the bottom 24, commencing just inside the slots 26c and curving downward and backward to the bottom which it fits into just inside the slot 26f. This plate 35 may be made of cottonwood veneer 80 or any other flexible material. It serves as a back, provides separate chambers for the clean and soiled toweling and also strengthens the inner case. 85

In the upper front portion of the lower 90 chamber 33 is a driver or feed control roll A and in the upper chamber 34, adjacent the bottom edge of the back 25, is a driven or take-up control roll B, both being mounted in the sides 26. These control rolls A and 95 B consist of a body 36 with an axle 37 extending therefrom through the sides 26, which axle is rotatably mounted in ball bearings 38 fitted into holes 26g cut in the sides 26. These rolls A and B have a roughened 100 peripheral surface 39 obtained by wrapping sand paper or a sheet of burred metal around the body 36, or the body 36 may be made of material roughened on the surface. A sprocket wheel 40 having teeth 41 is mounted on the end of each axle 37, on which wheels 105 a chain 42 is mounted which connects both sprocket wheels so that any motion imparted to either roll A or roll B rotates both. A pawl 43 is attached at one end to the axle 110 37 of the feed roll A, the other end of which pawl engages the teeth 41 of the sprocket wheel 40 which is mounted on the take-up roll B. Its position permits movement of the 115 rolls A and B in only one direction—to unwind the clean toweling and wind the soiled toweling—and locks them against movement in the opposite direction, so that the feed roll A cannot wind the clean toweling nor the take-up roll B unwind soiled toweling. 120

The elevator E, which is rounded at the bottom, has a chain 45 fastened to it at the top, which chain extends up through the rear hole 23d and then down through the front hole 23e, which holes are adjacent each other. A ring 46 is fastened to the free end of this chain 45, and its normal position is just under the top 23. When the clean toweling is being attached to the mechanism in the cabinet the elevator E is pulled up by the chain and 130

the chain 45 and ring 46 are caught in the notch 26b to hold the elevator up.

It has been found preferable to use lengths of toweling of approximately twenty-five yards, and when more toweling is required 5 a clasp 50 is used to connect two lengths by slipping said clasp into the loops 51 at the end of each length, as shown in Figure 8 of the drawings.

10 The operation of this towel cabinet is as follows:—

The door 20 is unlocked and swung open, the inner case 22 is pulled out as far as the locking bar 31 will permit, and the curtain 15 30 is pulled up as far as it will go and held in that position. A roll of clean toweling C is placed in the lower chamber 33, resting on the bottom 24 of the inner case 22, with its free end towards the front. The roll C is 20 unwound until a red line running across the toweling to mark the length required, becomes visible, which indicates a sufficient length has been unwound to make the necessary connections with the cabinet mechanism.

25 The free end of clean toweling goes around the back and over the driver control roll A. Because the inner case 22 has been pulled out the locking bar 31 is at this time to the rear of the roll A and out of the way, so there 30 is sufficient space for the hand to go between it and the back of said roll A to pull the toweling over the roll. The curtain 30 is allowed to drop and the free end of toweling 35 pulled out and over the top of said curtain 30 and run under the bottom 17 of the outer frame 15. The chain 45 is pulled outwardly raising the elevator E, and the ring 46 is caught in the notch 26b thereby holding the elevator E suspended. The toweling 40 is then pushed into the space 17a up the back and to the rear and over the towel rod 32 and under the driven control roll B and out of the cabinet. The inner case 22 is pushed back into the outer frame 15 and the curtain 45 45 slipped into the groove 17c where it remains, holding the inner case within the outer frame, serving as a guide for the exposed toweling and a guard for the roll of clean toweling. A winding stick 52 is put 50 through the loop 51 in the free end of the toweling and the stick is then inserted in the slots 26g and pushed until it rests by gravity on the take-up control roll B. The ring 46 is slipped out of the notch 26b and the elevator 55 allowed to drop, striking the toweling just in front of the towel rod 32 and carrying it downwardly, forming a loop extending from the top of the towel rod 32 down and under the elevator E and up to the soiled 60 toweling roll T. The elevator E now rests on the rubber bumpers 24e. Any slack in the toweling should be taken up by winding it around the stick 52, so that the toweling between the clean toweling roll and the soiled 65 toweling roll is fairly taut.

The door 20 is closed and locked and the cabinet is ready for use, with the toweling exposed in the opening 20b. The user inserts his fingers between the edge of the toweling and the door 20 and grasping it in back and front pulls it outwardly where it is ready for use. The act of pulling the toweling outwardly causes the driver or feed roll A, which is in contact with the toweling, to revolve which in turn causes the driven or take-up roll B to revolve, which is also in contact with the toweling, causing it to wind on the stick. It is the loop of toweling formed between the towel rod 32 and elevator E which makes it possible to automatically withdraw part of the used toweling within the cabinet, and at the same time wind another part of the used toweling around the stick 52. The act of pulling the toweling outwardly lifts the elevator E until its bottom is opposite the towel rod 32, which lifting frees the top of toweling running from the towel rod 32 under the elevator E and up again, one portion of which freed toweling permits the winding of the soiled toweling 70 on the soiled toweling roll while another portion permits the user to pull part of the soiled toweling out of the cabinet which provides the necessary slack or play to enable the user to freely move the clean toweling as he dries himself. If this soiled toweling were not withdrawn more clean toweling would be required as part of the clean toweling would have to furnish the necessary slack required 75 in the wiping operation. When the elevator E reaches its highest position which is opposite the towel rod 32, the driven or take-up roll B is prevented from any further rotation for no more soiled toweling is available 80 to be wound as long as the user holds the toweling outside the cabinet, and of course, the driver or feed roll A cannot rotate if the driven roll B cannot, with the result that only a limited length of clean toweling may be pulled 85 out by each user, thus definitely limiting the 90 service. It should be understood, in this connection, that there is nothing to prevent any one who does not pull the toweling outside the cabinet, from continuously unwinding all of the clean toweling and simultaneously winding 95 it on the soiled toweling roll T. This, however, would be purely wasteful, as the user must pull the toweling out of the cabinet in order to use it, and the length he may pull out at one time is definitely limited as heretofore explained. This length is determined by the distance the elevator E travels. 100

When the user has dried himself he releases the toweling, the elevator E drops on the toweling, drawing it within the cabinet.

When the supply of clean toweling is exhausted the door 20 is opened, and the winding stick 52 is slipped out of slots 26g and a clean roll inserted in the lower chamber 33.

If desired, the automatic take-up mech-

anism may be disregarded by running the toweling between the two rolls A and B just as explained, only ignoring the towel rod 32 in which case a loop would have to be left hanging outside.

While a specific embodiment of the invention has been illustrated and described the invention is not to be considered as limited to the particular combination and arrangement of parts as above described except as limited in scope by the appended claims.

I claim as my invention:—

1. A towel cabinet comprising an outer frame and an inner case to fit into said outer frame, a curtain adapted to slide vertically in said inner case, said outer frame having provision to cooperate with said curtain whereby said curtain prevents said inner case from being drawn outwardly when the cabinet is in use.
2. A towel cabinet comprising an outer frame and an inner case to fit into said outer frame, a curtain over which toweling passes adapted to slide vertically in said inner case, said outer frame embodying a bottom having a groove therein in which said curtain is adapted to fit when the cabinet is in use to hold said inner case within said outer frame.
3. A towel cabinet comprising a casing, a support for a towel supply therein, a feeding instrumentality above said support, a hinged door for the front of the casing having a closed upper panel and an open lower panel a support for a soiled portion of the towel opposite said closed panel, a curtain vertically slidable in guides in said casing and normally adapted to close said open panel, a cleat on said curtain between which and the upper wall of said open panel the user may draw the clean towel, said wall being in the path of said cleat to prevent raising of said curtain when said door is closed, the upward movement of said curtain when the door is open allowing access to the clean towel support.

CHARLES W. THOMPSON.
